UNITED STATES PATENT OFFICE.

ARTHUR C. FRANKLE, OF NEW HAVEN, CONNECTICUT, ASSIGNOR TO THE MORTIMER NEWMAN COMPANY, OF NEW HAVEN, CONNECTICUT, A CORPORATION OF CONNECTICUT.

DESIGN FOR AN ANIMAL FIGURE.

Application filed June 1, 1928. Serial No. 26,947. Term of patent 7 years.

To all whom it may concern:

Be it known that I, ARTHUR C. FRANKLE, a citizen of the United States, residing at New Haven, county of New Haven, State of Connecticut, have invented a new, original, and ornamental Design for an Animal Figure, of which the following is a specification, reference being had to the accompanying drawing, forming part thereof.

Fig. 1 is a side elevation of an animal figure showing my new design, and

Fig. 2 is a top plan view thereof.

The surface shading on the drawing represents contrasting colors.

I claim:

The ornamental design for an animal figure substantially as shown and described.

ARTHUR C. FRANKLE.
